UNITED STATES PATENT OFFICE

2,470,316

ROPE HOLDER

John Zin Miller, Hagerstown, Md.

Application September 22, 1947, Serial No. 775,427

6 Claims. (Cl. 24—134)

1

This invention relates to novel and useful improvements in rope engaging and locking means.

An object of this invention is to retain rope or the like in a selected locked position.

Another object of this invention is to provide means for carrying out the above mentioned function.

Another purpose of this invention is to provide a housing having side walls and resiliently biased adjustable means for engaging a rope and pressing the said rope against the bottom portion of the said housing.

Another purpose of this invention is to provide means for selectively pivoting the rope engaging means in various positions to compensate for selected size rope.

Another purpose of this invention is to provide friction conducive means in association with the said rope engaging means and means for limiting the pivotal travel of the said rope engaging means relative to the housing.

Another purpose of this invention is to provide a simple device which may be easily manufactured.

Ancillary objects and features of novelty will become apparent in following the description of the preferred form of the invention, illustrated in the accompanying drawings, wherein:

Figure 1 is a sectional view of the preferred form of the invention illustrating its use in conjunction with a selected size rope;

Figure 2 is a sectional view of the invention similar to that shown in Figure 1, illustrating the use of the invention in conjunction with a rope of a larger diameter;

Figure 3 is an elevational side view of the invention, and;

Figure 4 is a plan view of the rope engaging and locking means forming a part of the present invention and utilized therewith.

Referring now in detail to the illustrated preferred embodiment of the present invention, like reference characters are used throughout to indicate similar elements thereof.

This invention has been conceived and developed to provide improved clamping means utilized in conjunction with rope or the like. The invention further relates to a clamp of the nature which utilizes the tension in the rope for efficaciously clamping the same. There are many fields or environments wherein the invention is utilized such as clamping the ropes on trucks, anchoring bolts, securing rope utilized in conjunction with construction work and the like.

2

A housing having a base portion 10 is provided with side walls 12 and 14, respectively. A plurality of apertures 16 may be provided in the said base portion 10, for the obvious purpose of securing the said base to a suitable anchor. Any number of apertures 16 may be provided in accordance with the prerogative of the manufacturer.

Rope engaging and locking means is provided in association with the said housing. With this construction, reference is made particularly to Figure 2, wherein a bottom member 18 is disclosed having flanges 20, identical in nature, on each side of the said bottom portion 18. Especially, configured slots are provided in pairs on each of the said flanges 20. It will be noted that a first slot 22 extends substantially transversely of the said flange 20 while a second slot 24 communicates with the first slot 22 and runs substantially parallel through the longitudinal axis of the said flanges 20.

An aperture 26 is supplied in the bottom portion 18 for the purpose of detachably receiving a resilient biasing means or spring 28 therein. The opposite end of the spring 28 is detachably received around a pin 30 which extends across the walls 12 and 14.

A second pin 32 also extends across the said walls 12 and 14 and is selectively engageable by the aligned pairs of slots 22—24.

Of course, it is readily apparent that by utility of selected pairs of aligned slots the relative position of the rope engaging means may be adjusted in order to adapt the device for various sized ropes.

Means for limiting the travel of the said rope engaging means relative to the pivotal movement thereof is provided. This means may be noted as simple stops or inturned portions 34 and 36 respectively provided on the said walls 12 and 14. Also, friction conducive means is provided on the lower extremity of said rope engaging means and may be seen as the teeth 38.

Due to the extreme simplicity achieved by the present invention, a further description thereof is deemed unnecessary. However, it is apparent that various departures may be made from the illustrated embodiment of the invention without departing from the spirit thereof. Accordingly, limitation is sought only in accordance with the scope of the following claims.

Having described the invention, what is claimed as new is:

1. A rope holder comprising a housing having a base and sides, a rope engaging member, means for pivotally and adjustably supporting said mem-

ber in said housing, means for resiliently biasing said member toward said base, said supporting means including a pin secured to said sides, curved slots in said member selectively positioned on said pin.

2. A rope holder comprising a housing having a base and sides, a rope engaging member, means for pivotally and adjustably supporting said member in said housing, means for resiliently biasing said member toward said base, said supporting means including a pin secured to said sides, curved slots in said member selectively positioned on said pin, said resilient biasing means comprising a spring secured to said sides and said member.

3. A rope holder comprising a housing, having a base and sides, a rope engaging member, means for pivotally and adjustably supporting said member in said housing, means for resiliently biasing said member toward said base, friction conducive means associated with said member, and means for limiting the pivotal travel of said member, said supporting means including a pin secured to said sides, flanges on said member, pairs of aligned slots in said flanges having angularly disposed slots communicating with said first mentioned slots and selectively seated on said pin.

4. A rope holder comprising a housing having a base and sides, a rope engaging member, means for pivotally and adjustably supporting said member in said housing, means for resiliently biasing said member toward said base, friction conducive means associated with said member, and means for limiting the pivotal travel of said member, said supporting means including a pin secured to said sides, flanges on said member, pairs of aligned slots in said flanges having angularly disposed slots communicating with said first mentioned slots and selectively seated on said pin, said limiting means comprising a pair of stops secured to said sides engageable with said flanges.

5. A rope holder comprising a housing having a base and sides, a rope engaging member, means for pivotally and adjustably supporting said member in said housing, means for resiliently biasing said member toward said base, friction conducive means associated with said member, and means for limiting the pivotal travel of said member, said supporting means including a pin secured to said sides, flanges on said member, pairs of aligned slots in said flanges having angularly disposed slots communicating with said first mentioned slots and selectively seated on said pin, said limiting means comprising a pair of stops secured to said sides engageable with said flanges, said limiting means including a spring detachably secured to said pin and said member, said friction means comprising a plurality of teeth adapted to engage a rope.

6. A rope holder comprising a housing having a base and sides, a rope engaging member, means for pivotally and adjustably supporting said member in said housing, means for resiliently biasing said member toward said base, said supporting means including a pin secured to said sides, slots in said member selectively positioned on said pin.
